WITNESS:

Patented Sept. 21, 1926.

UNITED STATES PATENT OFFICE.

LEX W. HUBBARD, OF TARRANT, ALABAMA.

HEATER.

Application filed February 4, 1925. Serial No. 6,833.

The object of this invention is the provision of a boiler for use in heating buildings, characterized by simplicity in construction and reliability and efficiency in practical use.

5 To the attainment of the foregoing, the invention consists in the improvement as hereinafter described and definitely claimed.

In the drawing the figure illustrates a substantially vertical central sectional view 10 through the improvement.

The shell or jacket of the boiler 1 has formed therein but spaced therefrom a combustion chamber 2, the smoke flue 3 of which passes through the rear of the combustion 15 chamber. The top of the combustion chamber is disposed a considerable distance below the top of the shell, and the combustion chamber is provided with the usual grate 4 below which is the ash pit 5. The combustion chamber is joined to the side of the boiler approximately in a line with the grate 4.

Preferably integrally formed centrally on the top of the combustion chamber 2 there 25 is an inwardly directed substantially frusto-conical chamber 6 whose reduced end or mouth 7 projects beyond the top of the said combustion chamber.

On the top of the combustion chamber, 30 and surrounding the nozzle end 7 of the chamber 6 there is an annular flange 8, the same forming a pan on the top of the said combustion chamber.

Either integrally formed with or secured 35 to the center of the top of the boiler there is the reduced neck portion 9 of a substantially pear-shaped chamber 10. The bottom of the chamber 10 is rounded upwardly and inwardly, as at 11. The inwardly 40 rounded or flared portion 11 communicates with the chamber 10 and provides the same with a nozzle which is arranged directly below the neck 9 of the said chamber.

Screwed in a suitable boss on the top of 45 the boiler that communicates with the neck of the chamber 10 there is the steam or hot water outlet pipe 12.

The return pipe for the boiler is indicated 50 by the numeral 19, and the water feed pipe for the boiler is indicated by the numeral 23.

With my improvement all of the water in the boiler will be heated from the fire in the combustion chamber 2. However, the water directed by the pan 8 into the chamber 6 of the injector will be subjected 55 to the greatest amount of heat so that steam will be generated therein. As hot water always rises a determined amount of boiling water will be received in the pear-shaped chamber 10. The steam from the injector 60 6 is directed through the nozzle 11 at the bottom of the chamber 10 and this steam acting on the boiling water in the said chamber 10 will force the water through the top of the boiler into the pipe 12. The said 65 water, while still in heated condition will be returned through the pipe 19 to the boiler. Thus it will be noted that a continuous circulation of hot water is produced.

Having described the invention, I 70 claim:

A boiler having in its shell or drum a combustion chamber whose lower wall joins the fire box at a point above the ash pit and whose upper wall is arranged a considerable 75 distance below the upper wall of the boiler, there being an integral smoke flue between the side of the upper portion of the combustion chamber and one side of the boiler, said combustion chamber having a frusto-conical 80 water chamber whose lower and widened portion is received in the combustion chamber and whose reduced mouth portion is extended beyond the top of the combustion chamber, an annular flange on the top of 85 the combustion chamber surrounding the mouth of the water chamber, a pear-shaped chamber formed on and depending from the top of the boiler and received in the flange, said pear-shaped chamber having its bottom 90 rounded upwardly and inwardly to provide a water inlet mouth for the said pear-shaped chamber, pipes screwed in the top of the boiler, one of which communicates with the pear-shaped chamber, and an inlet water 95 pipe screwed in one side of the boiler.

In testimony whereof I affix my signature.

LEX W. HUBBARD.
